PAGING RECEIVER HOUSING

Arthur W. Schmidt, Chicago, Ill., assignor to Zenith
Radio Corporation, Chicago, Ill.

Filed Dec. 3, 1970, Ser. No. 26,265

Term of patent 14 years

Int. Cl. D14—03

U.S. Cl. D26—14

FIG. 1

FIG. 2

FIG. 3

FIG. 4

FIG. 5

FIG. 6

FIG. 1 is a perspective view of my design for a paging receiver housing showing the front, top and right side thereof;

FIG. 2 is a top plan view thereof;

FIG. 3 is a right side elevational view thereof;

FIG. 4 is a bottom plan view thereof;

FIG. 5 is a front elevational view thereof; and

FIG. 6 is a rear elevational view thereof.

The left side of the paging receiver housing is substantially the same as the right side.

I claim:

The ornamental design for a paging receiver housing, substantially as shown and described.
